PRESSURIZED FIRE EXTINGUISHER

Charles K. Huthsing, Sr., Culver City, Calif.

Application August 23, 1955, Serial No. 530,024

5 Claims. (Cl. 169—31)

This invention relates generally to pressurized fire extinguishers, and more particularly, to an improved head assembly for portable tank type extinguishers.

Portable tank extinguishers are well known in the art and generally include a head assembly embodying nozzle means and a lever actuated valve for releasing fluid under pressure within the tank out the nozzle. It is extremely important in such extinguishers that they may be capable of rapid and reliable operation. Towards this end, the valve means and lever in the head assembly should be designed to assure positive positioning of the valve when it is actuated to either an open or closed position.

It is also important in such extinguishers that the possibility of accidental operation be minimized. This factor is of particular significance when the fire extinguisher is being transported from one place to another under emergency conditions. In conventional constructions, the actuating lever for the extinguisher is disposed close to the carrying handle, or in some instances may act as the carrying handle itself. It will be evident, therefore, that unless the extinguisher is handled very carefully there is the possibility of inadvertent operation.

Bearing the above in mind, it is a primary object of the present invention to provide an improved head assembly for tank type pressurized fire extinguishers including a novel valve sealing means and locking means therefor in combination with a carrying handle. These elements are designed in such a manner that there is a minimum possibility of unintentional operation, and yet whereby a single, intentional manual movement is sufficient to ready the extinguisher for immediate operation.

More particularly, it is an object to provide a combination locking and carrying handle for a pressurized extinguisher in which the handle additionally provides a conveniently positioned member for co-operative gripping with the actuating lever when operating the extinguisher.

Still another object is to provide a sealing structure and material in the valve means in combination with the actuating lever and locking handle, which is extremely reliable, and long wearing in operation, but may be easily replaced if warranted, without the necessity of disassembling the entire head assembly.

These and other objects and advantages of the present invention are attained by providing, in a fire extinguisher head assembly, a valve body having an actuating lever pivoted thereto at a given point. A valve means, normally biased to a closed position, is arranged to be opened only upon pivoting movement of the lever. A handle is pivoted to the valve body at a point spaced from the given point at which the lever is pivoted and is provided with means for blocking the lever when the handle is in a first given position, whereby the lever is prevented from opening the valve means. Pivoting of the handle to a second position serves to simultaneously release the lever and also dispose the handle in a convenient grip-

2

ping position for operating the lever. By this arrangement the combined locking and carrying handle is not directly associated with the valve mechanism except through the action of the lever and, therefore, the valve construction may be simplified and thus rendered more reliable.

The valve means includes a plunger and valve member adapted to close an orifice between a valve chamber and a suitable nozzle forming part of the head assembly.

10 Rather than a conventional type valve sealing seat within the chamber surrounding the orifice, in accordance with a feature of the present invention, the valve member itself is provided with an annular frusto-conically shaped seal which seats against the periphery of the orifice when actuated towards closed position.

This seal is formed of a "cold flow" material which gradually, under pressure, is deformed to the exact contour of the orifice, and, thereby insuring proper sealing over a long life. Should it be desirable to change the seal, however, it may be simply replaced without the necessity of disassembling the entire head assembly other than mere removal of the plunger and valve member. An entirely new plunger and valve member with a suitable sealing means may then be substituted, or the seal itself may be removed from the valve member and a new seal placed in position.

A better understanding of the manner in which the improved valve means, locking feature, and handle in the head assembly of the present invention operate, will be had by referring to the accompanying drawings illustrating a preferred embodiment, and in which:

Figure 1 is an elevational view partly in cross section of the improved head assembly of this invention;

Figure 2 is a side view taken in the direction of the arrow 2 of Figure 1;

Figure 3 is a view similar to Figure 1 showing the head assembly in unlocked position with the actuating lever depressed for operation; and,

Figure 4 is an enlarged cross sectional view of the valve member incorporating the improved sealing means of the present invention.

Referring to Figure 1, there is shown a tank type portable fire extinguisher comprising a tank 10 having threadedly secured to its upper portion a head assembly valve body 11. As shown, the valve body 11 defines an interior valve chamber 12 having an orifice 13 communicating with a passage 14 and terminating in a nozzle 15. A valve member 16 is positioned within the chamber 12 and movable by means of a plunger rod 17 to open and close the chamber orifice 13.

Operation of the valve member 16 is effected by means of a lever 18 disposed at the top of the head assembly and pivoted to the valve body as at 19. The valve member 16 is normally held against the orifice 13 in its closed position by a biasing spring 20 within the valve chamber 12. Fluid is admitted into the chamber 12 through a discharge tube 21 extending down into the tank 10. The tube 21 is secured in position to the valve body 11 by a nut 22 opening within the bottom portion of the chamber 12. Movement of the valve member 16 to its open position is effected by pivoting the lever 18 about the pivot point 19 to depress the plunger rod 17.

In order to prevent accidental operation of the valve by the lever 18, there is provided, in accordance with one feature of the invention, a handle 23 pivoted to the valve body as at 24 at a point spaced from the pivot point 19 on the other side of the plunger rod 17. The upper portion of the handle 23 is forked to define two hooks 25 adapted to engage a locking pin 26 rigidly secured to the lever 18, when the handle 23 is in a first given position. From Figure 2, it will be evident that the forked, double

walled construction of the upper portion of the handle 23, including the hooks 25, enables pivoting movement of the handle 23 about the point 24 without interference with the plunger rod 17 in the head assembly.

Effective sealing of the plunger rod 17 at its entrance into the valve body 11 is provided by a nut 27 centrally apertured to receive the plunger rod, and threaded into the top of the valve body a given distance to leave an annular space about the rod to accommodate a seal 28. A compression spring 29 is arranged to surround the rod 17 and bear against the seal as shown. Threading down of the nut 27 will serve to compress the spring 29 and thus in turn compress the seal 28 against the rod.

In Figure 3, the handle 23 is shown in its unlocked position after being pivoted about the pivot point 24 to 15 disengage the locking pin 26, thereby leaving the lever 18 free to operate. In the new position of the handle 23, it will be noted that it forms a convenient gripping surface in co-operation with the lever 18 to permit ready depression of the lever 18 to push the plunger rod 17 downwardly into the valve body. Movement of the valve rod downwardly unseats the valve member 16 from the orifice 13 thereby permitting pressurized fluid from within the tank 10 to pass up through the discharge tube 21, into the valve chamber 12, through the orifice 13 and passage 14, and out the nozzle 15. When the lever 18 is released, the bias spring 20 within the valve chamber 12 returns the valve member to its closed position shown in Figure 1.

It is important that the sealing of the orifice 13 be absolutely fluid tight in order to retain proper pressure within the tank 10 and insure that the fire extinguisher is at all times ready for operation. To this end, the present invention provides an improved sealing means as a part of the combination in the head assembly. As shown clearly in the enlarged cross sectional view of Figure 4, this sealing means comprises an annular sealing material 30 having a control opening through which the plunger rod 17 passes. A retaining nut 31 is threaded on the end of the plunger rod 17, and an annular head 32 of diameter greater than the diameter of the control opening in the seal is spaced upwardly from the rod end a sufficient distance to accommodate the thickness of the sealing member. Tightening of the retaining nut 31 on its threaded connection to the rod 17 serves to securely hold the seal 30 in place.

The seal 30 is formed of a material that will "cold flow" under pressure. A preferred sealing material having this characteristic is teflon, which is also inert (as required) to carbon tetrachloride and other liquids conventionally used in the extinguisher. Thus, the seal 30 gradually deforms over a given time to completely cork the orifice 13, thereby affording an extremely effective valving means.

In the event replacement of the seal is necessary, the head assembly is removed from the tank 10 and the nut 22 supporting the discharge tube 21 from the bottom of the valve chamber 12. The spring 20 may then be withdrawn and the valve plunger rod 17 and member 16 easily removed. A new valve member may be inserted, or the seal 30 simply removed from the used valve member and a new seal inserted.

The operation of this improved extinguisher will be evident from the above description. When the fire extinguisher is not in use, the parts of the head assembly are in the position shown in Figure 1. In this position, the hooks 25 of the handle 23 encircle a sufficient circumferential portion of the locking pin 26 to prevent the handle 23 becoming disengaged from the locking pin unless intentional force is applied to the handle 23 in a counter clock-wise direction. In the position shown in Figure 1, the extinguisher may be easily transported about without the possibility of accidentally depressing the operating lever 18 since pivoting motion of the lever 18 is blocked by engagement of the locking pin 26 by the hooked portion 25 of the handle 23.

In operating the fire extinguisher, the operator need

simply grasp the handle 23 and move it upwardly to a position adjacent the operating lever 18 as shown in Figure 3. Such movement serves to simultaneously release the locking pin 26 and position the handle 23 adjacent the operating lever 18 in a convenient location for gripping, whereby the lever 18 may be easily depressed with one hand. In Figure 3, the lever 18 is shown in its depressed position in solid lines whereas its normal off position is shown in dotted lines.

Depression of the lever 18 moves the plunger rod 17 downwardly to open the chamber orifice 13 and permit pressurized fluid to pass up through the tube 21 and valve assembly out the nozzle 15. Release of the lever 18 results in the compression spring 20 urging the valve member 16 upwardly to closed position against the orifice. The fluid flow from the nozzle 15 will then be cut off and the extinguisher will not again operate until the lever 18 is depressed.

When it is desired to store the extinguisher, or simply transport it from one place to another, the handle 23 may be swung in a clock-wise direction about the pivot 24 to cause the hooked portion 25 to engage the locking pin 26, thus securing the lever 18 in its normal position shown in Figure 1. It will be noted that this locking handle does not act directly on the valve body or plunger rod but only on the lever 18. This construction permits the valve assembly and sealing means to be of simple structures minimizes the possibilities of part failures.

Modifications of the present structure within the scope and spirit of the present invention will occur to those skilled in the art. The improved head assembly is, therefore, not to be thought of as limited to the particular embodiment chosen for illustrative purposes.

What is claimed is:

1. In a fire extinguisher head assembly including a valve body having a lever pivoted thereto and valve means normally biased to closed position and adapted to be opened only upon pivoting movement of said lever, the combination comprising: a manually grippable handle extending outwardly from said valve body, said handle being pivoted to said valve body at a point spaced from the point at which said lever is pivoted; and co-functioning means on said handle and lever blocking said lever from pivoting, whereby said lever is prevented from opening said valve means, said means being released from blocking said lever upon pivoting of said handle to a given position.

2. A head assembly according to claim 1, in which said handle, when pivoted to said given position, is disposed adjacent said lever to provide convenient co-functioning hand gripping means in co-operation with said lever for pivoting the same.

3. In a fire extinguisher comprising a tank and a head assembly having a nozzle and a valve chamber for passing fluid under pressure within said tank to said nozzle, the combination comprising: a valve body defining said chamber; a valve member in said valve chamber normally closing said chamber off from communication with said nozzle, said valve member having plunger means extending through said valve body to the exterior thereof; a lever pivoted to said valve body at a point spaced to one side of said plunger means and adapted to engage said plunger means upon pivoting movement to move said valve member and open said chamber to communication with said nozzle; a manually grippable handle extending outwardly from said valve body, said handle being pivoted to said valve body at a point on another side of said plunger means; and means on said handle adapted to engage said lever when in a first position to block said lever against pivoting movement whereby said lever is prevented from moving said plunger means, said means on said handle being released from blocking said lever upon pivoting of said handle to a given position.

4. A fire extinguisher, according to claim 3, in which

said valve chamber includes an orifice, said valve body comprising a frusto-conical seal having a central opening and sloping sides adapted to seal said orifice; said plunger means comprising a rod passing through said orifice and said central opening of said seal; an annular bead about said rod at its point of entrance through said seal, said bead having a diameter greater than the diameter of said central opening; and a retaining means secured to the end portion of said rod, whereby said seal is secured between said bead and said retaining means.

5. A fire extinguisher according to claim 4, in which said seal comprises a cold flow material whereby it is adapted to sealably engage the entire periphery of said orifice.
